United States Patent

Des. 241,830
Patented Oct. 12, 1976

241,830

AUTOMOBILE WHEEL

Philip G. Patch, Laguna Beach, Calif., assignor to
Keystone Products, Inc., Ontario, Calif.

Filed Jan. 8, 1976, Ser. No. 647,682

Term of patent 14 years

Int. Cl. D12—16

U.S. Cl. D12—211

FIG. 1.

FIG. 2.

FIG. 3.

FIG. 4.

FIG. 1 is a top front perspective view of an automobile wheel showing my new design;

FIG. 2 is a front elevational view thereof;

FIG. 3 is a bottom rear perspective view thereof, partially cut away for clarity of illustration; and

FIG. 4 is a rear elevational view thereof.

I claim:

The ornamental design for an automobile wheel, as shown.
